UNITED STATES PATENT OFFICE

2,561,037

FINISHING METHOD AND APPARATUS

William T. Stanley, Gates Mills, Ohio

Application August 14, 1945, Serial No. 610,741

2 Claims. (Cl. 51—164)

1

This invention relates to the finishing of articles by the mechanical action of various articles upon each other or the interaction of such articles and other solid objects, such as when subjected to an abrasive, grinding or burnishing operation.

An object of the invention is to provide an improved method of abrading, grinding, burnishing and the like which may easily be performed.

Another object is to provide an improved method of abrading, grinding, burnishing and the like which may be performed with the use of little power.

Another object is to provide an improved method of abrading, grinding, burnishing and the like which will be extremely rapid.

Another object is to provide an improved method of abrading, grinding, burnishing and the like in which the abrasive, grinding or burnishing action may be controlled accurately.

Another object is to provide an improved apparatus for abrading, grinding or burnishing which will be simple in construction.

Another object is to provide an improved apparatus for abrading, grinding or burnishing which may be easily manufactured.

Another object is to provide an improved apparatus for abrading, grinding or burnishing which will be efficient in operation.

Another object is to provide an improved apparatus for abrading, grinding or burnishing which may be easily loaded and emptied.

Another object is to provide an improved apparatus for abrading, grinding or burnishing which will be economical both in manufacture and operation.

Another object of the invention is to provide an improved apparatus for abrading, grinding or burnishing in which a variety of materials may be used to produce different results.

Other objects will hereinafter appear.

The invention will be more apparent from the description of one practical embodiment thereof, illustrated in the accompanying drawing, in which:

Figure 1 is an end elevational view of a machine for practicing the invention;

Figure 2 is a side elevational view of the machine of Figure 1;

Figure 3 is a fragmentary transverse sectional view taken on the line III—III of Figure 2; and

Figure 4 is a transverse sectional view taken on the line IV—IV of Figure 3.

In the drawing a machine is illustrated which is intended for the removal of burrs, sharp edges, corners and the like from metal objects, this operation being what is commonly known as "tumbling."

In previous tumbling operations, it has been customary to place a number of the articles to be finished in a drum, together with abrasive

2

material, and frequently water, and, after closing the drum, to rotate the same so that the articles and the particles of abrasive material will be carried partially around the drum by its rotation to a point where they will fall under the influence of gravity, the impingement of the articles and abrasive particles on each other serving to wear, abrade or grind the projecting burrs, sharp edges, etc., to produce the desired finish.

The force which was applied to the articles was due solely to gravity acting upon them and the other materials within the drum, and so would be a function of the distance through which they might fall and their respective weights.

Obviously the weight of either the articles or the pieces of abrasive material were in proportion to their size and specific gravity. If the articles had small holes or narrow notches or slots, small particles of the abrasive material would have to be used to penetrate these openings, and these particles, in turn, due to their smallness would be relatively light. Consequently, their abrasive or similar action on any given contact with the article edges was very slight.

Thus, a great many cycles of the drum were required for the removal of even very small amounts of material.

According to the present invention, forces are introduced which, while, of course, are still proportional to the mass of articles and particles, but are not limited by the force of gravity acting thereon, as the invention replaces or augments this force with any desired amount of centrifugal force.

The mechanism illustrated for this purpose consists of a framework including two triangular frames 1 connected by parallel supports or sills 2, all conveniently being formed of channel shaped or similar steel sections welded together. On both of the frames are carried bearings or journals 3 supporting a horizontal shaft 4.

This shaft may be driven from a motor 5 carried upon the base, as by a belt 6 and stepped pulleys 7 and 8.

Fixed to the shaft 4 are two spiders 9, each shown as having four arms, in which are trunnioned four receptacles 10.

The containers 10 are shown as generally rectangular open-topped boxes, the tops being closed by lids 11, secured to the container by pivoted bolts and wing nuts 12.

A lining 13 may be provided for the container and a gasket 14 may be interposed between the container top and the lid, so that when the lid is clamped shut, a watertight seal is produced.

Centrally, on the ends of the container, are mounted sockets 15, shown to an enlarged scale in Figure 3, these sockets each being provided

with a non-circular opening, illustrated as square in this figure.

Into the socket 15 at the left hand end of the container (as seen in Figure 2) projects the squared end 16 of a shaft 17 journaled in one end of an arm of spider 9. The squared end of the shaft is held in the socket by a headed pin 18, which, in turn, is retained by a spring clip on split pin 19 passing through a perforation in the end of pin 18 remote from its head.

The outer end of shaft 17 has fixed to it a sprocket 20, around which passes a chain 21, the chain also passing around a fixed sprocket 22 secured to a sleeve 23 fixed to bearing 3, shown at the left hand side of this figure.

Thus, there are four stationary sprockets 22 and four chains 21 connecting to the various sprockets 20 in the four-container form of device illustrated.

The socket 15 at the right hand side of Figure 2 receives the squared end of a short stub shaft 24 journaled in the end of one of the arms of the spider 9 at the right hand side of the figure, this stub shaft being secured to the socket by a headed pin 18 and split pin 19, as is the shaft 17. The stub shaft is provided with a knurled or other easily grippable head 25.

The sprockets 20 and 22 may be chosen in any desired ratio, and, dependent upon this ratio, the containers 10 may revolve about their trunnion-like connections of the sockets 15 and shafts 16 and 24 at any desired speed in relation to the speed of the rotation of shaft 4, while the speed of the latter, of course, will be determined by that of motor 5 and the steps of pulleys 7 and 8 which are engaged by the belt 6.

Thus, the containers may be given a planetary motion, revolving in circular orbits about the axis of shaft 4 at any desired predetermined speed, and rotating on the axes of shafts 17 and 24 also at any desired preselected speed.

In practice, I have found that a ratio of 1 to 1 for sprockets 20 and 22 is very satisfactory, and this, of course, maintains the containers always in position with their lids uppermost, the containers traveling in the manner of the case of a "Ferris" wheel.

By imparting sufficient velocity of rotation to the shaft 4, and thus to the spiders and containers, sufficient centrifugal force is applied to the contents of the containers (these contents 26 consisting of parts to be finished and abrasive material such, for instance, as granite chips, to which may be added water if desired) and as these materials are carried around by the container traveling through its orbit, the contents are shifted from side to side, being in the bottom when the container is in its lowermost position, against the outer side in intermediate positions, and pressing against the top when in its uppermost position.

The force with which they press against these sides, of course, depends on the speed of rotation, and may, therefore, be varied as desired. It is, consequently, independent of the specific gravity of the articles themselves, or of the abrasive material, but is dependent solely upon the mass and velocity of these substances.

In this manner a much quicker finishing operation may be performed, and it is also possible to use relatively small quantities both of articles to be worked upon and of finishing materials in each container. This is a distinct advantage, particularly in the finishing of small articles which are difficult to separate from large masses of finishing material.

While the material for operating upon the articles is shown as abrasive, it may be a material which has a burnishing, crushing, or similar action, or the articles alone may act upon each other, in which event, with reference to any one article, the other articles constitute the "working material." Hence, the term "working material" will be used in the claims to define any substance capable of acting on the articles in a mechanical manner, whether by abrasion, burnishing, crushing or the like, or to other articles, and will be understood to include both solids and liquids as well as mixtures of solids and liquids.

Also, the process and apparatus may be used when the desired product is the complete reduction of the "articles" to a pulverized, or granulated or other finely divided state. All such operations are, therefore, to be comprehended by the terms "finishing" and "finishing articles" as used in the claims.

While I have described the illustrated embodiment of my invention in some particularity, obviously many other embodiments, variations, and modifications will readily occur to those skilled in this art, and I do not, therefore, limit myself to the precise details shown and described herein, but claim as my invention all embodiments, modifications and variations coming within the scope of the appended claims.

30 I claim:

1. A machine comprising a base, horizontally arranged bearings carried by said base, a horizontal shaft rotatably mounted in the bearings, an electric motor connected to said shaft, supporting arms fixed to the shaft, stub shafts journaled in the ends of said arms, driving connections between some of said stub shafts and the base, and a plurality of containers pivotally supported on said stub shafts and rotatable therewith, the containers and stub shafts having telescopically engaging non-circular portions.

2. The method of finishing articles which comprises confining a loose mass of articles and finishing material in a container having a volume substantially twice as great as the volume of said loose mass, revolving said container about an axis external thereof in an orbit at such a speed as to cause centrifugal force to overcome the effect of gravitational forces acting on the mass and maintaining the container in such an angular position with respect to an axis passing therethrough and parallel to the first axis that the resultant force acting on the loose mass within the container will cause the same to rotate relative to the container about the axis passing therethrough.
